(57) **CLAIM**

The ornamental design for a fork lift truck, as shown and described.

DESCRIPTION

FIG. 1 is a perspective view of the fork lift truck, showing the left side, front and top thereof;
FIG. 2 is a front view of the fork lift truck of FIG. 1;
FIG. 3 is a rear view of the fork lift truck of FIG. 1;
FIG. 4 is a left side view of the fork lift truck of FIG. 1;
FIG. 5 is a right side view of the fork lift truck of FIG. 1;
FIG. 6 is a top view of the fork lift truck of FIG. 1; and,
FIG. 7 is a bottom view of the fork lift truck of FIG. 1.
The broken lines shown in the drawings represent portions of the fork lift truck that form no part of the claimed design.
